UNITED STATES PATENT OFFICE.

ARTHUR HIRSH, OF CHICAGO, ILLINOIS.

OIL-CUP.

1,165,333.

Specification of Letters Patent. Patented Dec. 21, 1915.

Application filed May 27, 1914. Serial No. 841,193.

To all whom it may concern:

Be it known that I, ARTHUR HIRSH, a citizen of the United States, residing at Chicago, in the county of Cook and State of Illinois, have invented new and useful Improvements in Oil-Cups, of which the following is a specification, reference being had to the accompanying drawings, forming a part thereof.

10 The purpose of this invention is to provide an improved form of closed oil cup of the character which is designed to hold the oil by means of an absorbent material saturated therewith and adapted to be compressed to discharge the oil to the bearing to which the cup is attached.

It consists in the elements and features of construction shown and described, as indicated in the claims.

20 In the drawings:—Figure 1 is a side elevation of an oil cup embodying this invention. Fig. 2 is an axial section of the device showing the two members separated. Fig. 3 is a top plan view of the lower member or body of the device with the cap or cover removed. Fig. 4 is a section at the line 4—4 on Fig. 1.

The oil cup shown in the drawings is designed to be made of steel stampings, and 30 comprises two members in addition to a spring member forming pintles by which the two principal members are engaged. The outer and upper member, 1, is in the form of a cylindrical cap having formed in 35 its cylindrical wall a spiral bead, 2^a, forming interiorly a spiral groove or channel, 2, said groove and channel extending somewhat more than one hundred eighty degrees around the cap, and a corresponding spiral 40 series of interior indentations, 3, forming exterior bosses, 3^a, which series of bosses and indentations commences at a point diametrically opposite the lower end of the spiral groove and extending around the opposite 45 half of the cap from that occupied by the groove overlaps the latter to the extent that said spiral groove and said spiral series of indentations each exceed one hundred eighty degrees. At the lower edge of the cap, immediately below the lowest of the indentations and the end of the spiral groove, there 50 are formed slight notches, 4, 4, to constitute approaches to the groove and indentations, respectively. The lower member of the device is a cup, 5, which is formed with an

hexagonal shoulder, 5^a, and a threaded terminal, 5^b, by which it is adapted to be screwed into the bearing to be oiled. The upper portion of the cup is cylindrical, adapted to fit snugly within the cap member, 1,

6 is a pintle bar extending diametrically with respect to the device and mounted in the cup member, 5, with its ends protruding at diametrically opposite points therefrom 65 near the upper edge thereof, so that said ends constitute pintles, 6^a, adapted to engage, respectively, the groove, 2, and the indentations, 3. This pintle bar is bowed between its ends, the bow, 7, being adapted to 70 droop into the cup member, 5, as seen in Fig. 2, and the pintle bar is thereby adapted to be sprung into place in the cup member, and its ends are held yieldingly protruded therefrom for engagement with the groove 75 and indentations of the cap member.

It will be understood that the cavity enclosed by the cup and cap is designed to be filled with oil-saturated waste, which will be compressed for squeezing the oil out 80 of it into the bearing by telescoping the two members, 1 and 5, more or less. A suitable quantity of saturated waste being supplied to substantially fill the entire cavity when the members are telescoped to the least extent which will effect the engagement of the pintles in the lower end of the groove, 2, and the lowest of the indentations, 3, the pintles are thus engaged by starting them in by way of the notches, 4, 4, and pressing 85 the members together until the pintles snap into the groove and indentation, respectively. Further engagement for compressing the oil-saturated waste will be made by 90 rotating the cup, in which action the spiral grooves engaged by one pintle steers the cap after the manner of a screw thread, causing the opposite pintle to follow the proper spiral course for engaging the indentations successively, the ends of the 95 pintles being rounded so that they can be forced out of the indentations by turning the cap, will nevertheless engage the indentations sufficiently to substantially lock the cap securely at all positions to which it may be 100 screwed. By this means, it is possible to make the connection of the cup and cap as secure against unscrewing as could be done by a fine low-pitched screw thread. In 105 practice, the distance from indentation to 110

indentation in the spiral series of indentations, 3, may be substantially equal to one full turn of a thread of sufficiently low pitch to be safe, so that the cap can be adjusted 5 by steps equivalent to one complete turn of such a screw thread and be secure at all stages of the adjustment, the entire movement for compressing the mechanism amounting to only half a turn as against ten 10 or twelve turns which would be required if the screw threading action were employed.

An important advantage of the device is that it can be manufactured at very much less cost than would be involved in cutting 15 the screw thread.

I claim:

1. An oil cup comprising a cup member and a closure therefor adapted to telescope with each other, the exterior member having 20 interiorly at one side a spiral groove and at the other side a correspondingly spiral row of indentations, the interior member having pintles adapted for engaging respectively the groove and the indentation.
2. An oil cup comprising a cup member and a closure therefor adapted to telescope with each other, the exterior member having interiorly at one side a spiral groove and at the other side a correspondingly 25 spiral row of indentations; spring-connected pintles mounted in the inner of said members and protruding yieldingly for engage-

ment respectively with the spiral groove and the indentations.

3. An oil cup comprising a cup member 35 and a closure therefor adapted to telescope with each other, the exterior member having interiorly at one side a spiral groove and at the other side a correspondingly spiral row of indentations; a pintle device 40 consisting of a spring rod bowed between its ends, the ends being engaged with the inner of said members and protruding yieldingly therethrough for engagement respectively with the spiral groove and the indentations 45 of the exterior member.

4. An oil cup comprising two members adapted to telescope with each other, one of said members having in the cylindrical surface contiguous to the other member at 50 one side a spiral groove, and at the opposite side a correspondingly spiral row of indentations, the other member having pintles for engaging, respectively, the groove and the indentations, one of the pintles being elastically yielding for engaging and being disengaged from the indentations. 55

In testimony whereof I have hereunto set my hand, at Chicago, Illinois, this 15th day of May, 1914.

ARTHUR HIRSH.
